UNITED STATES PATENT OFFICE

161,794

MATCH BOOK DISPLAY STAND

Joseph Shapiro, St. Louis, Mo., assignor to Universal Match Corporation, St. Louis, Mo., a corporation of Delaware

Application April 19, 1950, Serial No. 9,334

Term of patent 14 years

(Cl. D80—9)

To all whom it may concern:

Be it known that I, Joseph Shapiro, a citizen of the United States, residing at the city of St. Louis, State of Missouri, have invented a new, original, and ornamental Design for a Match Book Display Stand, of which the following is a specification, reference being made to the accompanying drawing, forming a part thereof.

I claim:

The ornamental design for a match book display stand, substantially as shown.

JOSEPH SHAPIRO.
